GAS BURNER BODY

Robert E. Schreter, Malverne, N.Y., and John J. O'Hara,
Glen Ridge, N.J., assignors to Hauck Manufacturing
Company, Brooklyn, N.Y., a corporation of New York

Filed Oct. 17, 1962, Ser. No. 72,161

Term of patent 7 years

(Cl. D81—10)

FIG. 1 is a front view of a gas burner body showing our design;

FIG. 2 is a rear view of the same;

FIG. 3 is a side elevation of the same; and

FIG. 4 is a top plan view of the same.

We claim:

The ornamental design for a gas burner body, substantially as shown.
